ROAD JOINT MACHINE

John N. Heltzel, Warren, Ohio

Application June 20, 1932, Serial No. 618,359

29 Claims. (Cl. 94—39)

The present invention relates to improvements in road joint machines, and is a continuation in part of my copending application entitled Road building apparatus, filed December 19, 1929, Serial No. 415,318.

In common with the objects of that prior application, the present invention aims to provide an improved apparatus or device for operating upon concrete roads to install joint material therein, whereby the concrete roads will be divided into separable slabs capable of independently contracting and expanding incident to changes in temperature without resulting in haphazard cracking and breaking of the concrete throughout the slabs and in avoidance of upheaval of the road due to frost and freezing.

It is another object of the invention to provide an improved joint which will control the cracking of the slabs from the longitudinal monolith into which the concrete road is molded, the joint preventing the seepage of surface water into the crack beneath the joint, and thus avoiding deterioration of the road from such seepage and from the water freezing in the road joints and cracks.

A further object of the invention resides in providing an improved joint for the roads, which will avoid the surface spalling of the concrete at the joint, and which will tend to maintain for a long time the joint in a neat and water proof condition.

A further object of the invention is to provide an improved device for the installation of the joint material, whereby the material may be deposited at a greater depth and in a proper position and location within the plastic mass of the concrete body.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a perspective view, with parts broken away, showing an improved joint and a method and device for installing same.

Figure 1—A shows a modified form of joint in the concrete.

Figure 1—B shows a further modified form of the joint.

Figure 2 is a vertical fragmentary section of a road with one form of the improved joint therein.

Figure 3 is a similar view with a slightly modified form of joint.

Figure 4 is a fragmentary perspective view with parts broken away, showing a further modified form of joint and method for installing same. 5

Figure 5 shows a similar view illustrating a further modification.

Figure 6 is a perspective view of an improved machine for slotting and installing joint material shown in connection with a partly broken 10 away slab of concrete.

Figure 7 is a perspective view of the installing blade with a fragment of the joint material engaging same and illustrating a sectional construction of the blade. 15

Figure 8 is a view similar to Figure 6 showing a modification involving the installation of two joint strips.

Figure 8—A is a fragmentary perspective view showing an inverted T-shaped joint produced 20 with the apparatus indicated in Figure 8.

Figure 8—B is a similar view showing a modified construction of inverted T-joint also produced by the apparatus illustrated in Figure 8.

Figure 9 is a perspective view of a modified 25 form of implement for installing doubled joint material shown as engaged with the concrete slab shown partly away and partly in section.

Figure 10 is a fragmentary perspective view of joint material deposited by the device of Figure 9. 30

Figure 11 is a perspective view, with parts broken away and parts shown in section of a further modified form of apparatus shown in connection with a concrete slab partially broken away and partially illustrated in section. 35

Figure 12 is a fragmentary perspective view of a concrete slab showing joint material deposited therein as by the machine of Figure 11.

Figure 13 is a perspective view, with parts broken away and parts shown in section, of a 40 further modified form of machine for installing doubled joint ribbon or material.

Figure 13—A shows the cutter projecting down through the slot.

Figure 13—B shows a modified form of cutter. 45

Figure 14 is also a perspective view, partly broken away and partly illustrated in section, showing a modified form of joint installing apparatus.

Referring more particularly to the drawings, 50 and for the present to Figure 1, attention is called to the fact that this figure corresponds to Figure 36 of my prior application aforesaid Serial No. 415,318.

In this Figure 1 is shown a blade 15 of inverted 55

U-shaped cross section having out-turned flanges 16 to move on the surface of the concrete. A plate 17 is mounted within the blade 14 and has an inclined edge 18 with the rear portion of the plate 17 of reduced height and preferably projecting from the rear end of the blade 15. A strip 19 of paper, or other foldable material, is fed over the inclined edge 18 of the plate 17 and folded downwardly by grooved folding discs 20 overlapping the upper edge of the plate 17, so that the strip 19 of tar paper or the like will be deposited in the concrete with the side edges lowermost and the fold or bight uppermost. The blade 15 and the blade or plate 17 may be moved forwardly in the concrete to deposit the folded strip 19 in rear.

Referring more particularly to Figure 2, which corresponds with Figure 33 of the co-pending application aforesaid, in this figure there is illustrated a strip 21 installed in a horizontal plane below a groove 21^a formed in the plastic concrete or slab 22. In the groove 21 is poured or inserted a filler material 23.

When the concrete sets and becomes hard, or when the temperature thereof is lowered, a crack 24 will occur beneath the groove 21^a or joint material 23. This crack is controlled by the plane of weakness created by grooving the concrete. In this way the crack is controlled and results in forming slabs of predetermined size. Such slabs may contract and expand in obeyance to atmospheric and temperature conditions quite independently of one another so that such atmospheric changes will no longer result in haphazard cracking of the roadway. The joint material 23 will seal the joint and the strip 21 will further protect the crack 24 from the seepage of water and from foreign material getting into the crack.

Figure 3 corresponds to Figure 34 of my co-pending parent application. In this figure the strip 25 is folded upwardly or into substantial U-shape below the filler or joint material 23. This strip 25 may be installed by the method and tools disclosed in my Patent No. 1,697,563, granted January 1, 1929.

Referring more particularly to Figure 4, the subject matter of this figure is not specifically disclosed in the parent application but the germ of the idea is in that parent application.

This Figure 4 shows a complete joint strip 26 embedded below the surface in the concrete slab 22 and being fashioned in a U-shape. At the forward portion of the figure a joint depositing and alining blade 27 is shown with its lower portion engaging the strip 26. At the rear part of the figure is shown a body of tar, asphalt, bitumen or composition material 28 deposited in the separation made by the blade 27 after such blade 27 has been drawn forwardly or otherwise removed. The body 28 forms a sealing deposit in the groove. The U-shaped strip 26 forms a pocket to retain the sealing material 28 in the groove, so that, when the longitudinal break 24 develops below the strip 26, the sealing material will not seep through the crack 24. The dowel bar 29, which extends transversely across the joint beneath the strip 26 will prevent the lateral separation of the adjacent slabs defined at opposite sides of the crack 24. Consequently the dowel bar will relieve the tension from the strip 26. It is to be understood that the strip 26 may consist of any suitable material, such as copper or non-corrosive steel, asphaltic paper or the like.

Referring more particularly to Figure 5, the joint strip 30 in this case projects substantially

to the top surface of the concrete slab 22. In other words the joint strip 30 extends up on both sides of the alining blade 27 substantially to the top edge of that blade and to the surface of the concrete road. The blade 27 is employed substantially as below described in connection with Figures 6 and 7.

Referring more particularly to Figures 6 and 7, a tubular or trough-shaped blade 31 is moved through the plastic concrete for the installation of the U-shaped strip 32. This strip 32 forms a pocket to retain joint filler or any suitable sealing material which may be deposited in the joint as more clearly described in connection with Figure 4.

The joint material 32 comes off a roll 33 carried freely on a shaft 34, which shaft is supported in brackets 35 having slots 36 therein which slots extend substantially vertically and are adapted to be engaged with bolts or other supporting means on a carriage or finishing machine. By the tightening and loosening of the bolts the vertical adjustment of the device may be secured.

The joint strip material in flat condition coming off the roll 33 is caused to pass under the longitudinal flat folding blade 37, shown more particularly in Figure 7. This flat blade 37 is seated within the trough-shaped blade 31. As the flat strip of material unwinds from the reel, such strip is drawn under the flat blade 37. The blade 31 folds the strip into a U-shaped section, as indicated at 32. This inner blade 37 may project any desired distance rearwardly of the trough-shaped blade 31, so that a substantially long blade, if desired, may be trailed in unison with the trough-shaped blade 31. The inner or folding blade 37 is mounted or carried on the trough-shaped blade 31 by an arch member or bracket 38 and the adjusting screw 39 which engages through the bracket 38 and has either pivotal or fixed connection with the forward portion of the blade 37. The threaded rod 39 and its hand wheel provides for the independent vertical adjustment of the forward end of the folding blade 37. An additional arch member or bracket 40 is mounted on the trough blade 31 and supports an adjusting screw 41 which engages with an intermediate or rear portion of the folding blade 37, whereby to manipulate the rear end of the folding blade 37 to the end that pressure on the strip 32 may be regulated.

At the extreme rear end of the folding blade 37 there is provided an edging tool 42 to round the edges of the joint progressively as the apparatus is trailed longitudinally through the concrete. It will be understood that the folding blade 37 will hold the strip 32 depressed in the concrete and maintain it to perfect longitudinal alinement, while the necessary finishing operations are performed over the top of the blade by a suitable finishing member represented at 43. This member 43 may be supported by the carriage, or may be operated manually on the surface of the roadway, it being understood that the blade 37 may trail for as much as twenty feet rearwardly of the carriage. In other cases it will be desirable that the blade 37 terminate at a very short distance behind the carriage; or for that matter such blade 37 may terminate within the limits of the carriage. After the folded joint strip 32 or joint retainer has been deposited in the plastic concrete, the joint may be filled with a suitable sealing material.

Referring more particularly to Figure 7, there is here shown more clearly the joint-folding 75

blade 37. It will be noted that the blade is cut off on an angle, as shown at 44, whereby the joint strip will be folded gradually as it is drawn under the folding blade.

It is desirable that the folding blade 37 be regulated as to length and consequently the same may be composed of a number of sections of the same or varying lengths. These sections may be added to or removed to secure a folding blade 37 of requisite length to suit local conditions. The main part of the blade 37 is shown in Figure 7 in connection with one of its sections 37a. One end of the section 37a is slotted as indicated at 45 and a pin 46 is extended across the slot in position to engage and interlock with an undercut notch 47 in the tenon bar 48 which projects from the rear of the main blade 37 in position to enter the slot 45. According to the same construction other sections of the blade may be detachably engaged with one another until a blade of requisite length is had. The length of the blade 37 will depend on the local conditions and the consistency of the concrete, it being understood that, when either quick setting or stiff concrete is used, a shorter length of blade is desirable.

Referring more particularly to Figure 8, an implement is shown for installing a flat longitudinal joint strip, which joint strip is indicated in Figure 2 by the numeral 21.

In this case the strip is not folded but is unwound from a reel 49 of joint strip material wound upon a shaft 50 which is supported in a bracket 51. This strip from the reel 49 is moved down into the tube 52 which extends to a proper depth below the surface of the concrete slab 22. This strip 21 in the flat position as shown embedded in the concrete will serve to seal the bottom of the joint as indicated. The strip 21 may consist of a mastic or premolded material, and the dowel bars 53 are preferably inserted transversely beneath the strip 21, as shown, to prevent the separation of the slabs and likewise the tearing of the strip. A suitable joint is formed above the strip, which may consist of either a poured joint or a ribbon joint as might be required. In some cases the flat ribbon strip may consist of ribbon steel and where this ribbon steel is of substantial width and strength it will form a bond with the concrete, serving as a tying element to tie the adjacent slabs together to prevent separation when the concrete cracks below the joint. It is desirable to produce a groove 54 in the bottom of the slab longitudinally, and directly under the center, of the longitudinal axis of the strip.

The bracket 51 and the tube 52 may be carried by a blade 55 having an inclined forward edge to facilitate movement through the concrete. This blade carries an outstanding slotted arm 56 by which it may be adjustably secured to parts of a bridge or finishing machine. In this way the entire implement may be adjusted as to height or depth in the concrete and the depth of the joint strip 21 may be adjusted and regulated.

Referring more particularly to Figure 8-A, the flat strip 21 is shown as deposited in the slab 22 at an appropriate depth and having its flatwise dimension disposed in the horizontal or substantially parallel with the surface of the pavement although sunk below the same. A removable joint strip, such as the blade 37 illustrated in Figure 7 may be inserted in the plastic concrete above the joint strip 21 and later re-

moved, thereby producing an open groove 57 which is later filled with sealing material 58. It will be understood that when the crack 24 develops under the strip 21 the poured material 58 will not seep down into the crack 24.

Referring more particularly to Figure 8-B the parts are the same as described in connection with Figure 8-A except that a vertical ribbon strip 59 is installed in the concrete against the horizontal strip 21; and this vertical joint strip 59 may be saturated with the mastic material if so desired.

The machine, illustrated in Figure 8, may be equipped with means for installing this vertical joint strip 59. To accomplish this purpose a 15 second roll of joint material 60 is mounted upon the shaft 59 along side the roll 49 for the horizontal joint strip 20. The roll 60 is unreeled or unwound and passed downwardly through a vertical hollow tube or blade 61, the lower portion of which extends perpendicularly to the central part of the horizontal tube 52. These two tubes may connect and be in substantially the form of an inverted T if desired as shown in Figure 8. Should it be desirable to waterproof the vertical strip 59, a container 62 for mastic material is provided connecting by means of a tube 63 with the vertical joint tube 61. Thereby the mastic material is delivered to the vertical strip 59 and this sealing material may also be forced into the lower horizontal tube 52 so as to coat the horizontal strip 21 if desired. This double coating may be had by reason of the intercommunicating formation of the vertical and horizontal tubes 61 and 52. Any appropriate support may be provided for the mastic container 62.

The surfacing device 43 may be operated over the top of the vertical tube 61 and over the joint strips either manually or by machine operation.

If desired the surfacing member 43 may operate either above the tubes 61 and 52 or may operate over the joint strips 21 and 59 in rear of the tubes 52 and 61; or in other words after the tubes have been drawn forwardly.

It is to be understood that instead of using the vertical joint strip 59, suitable plastic material may be projected through the vertical tube 61 to be deposited in the plastic concrete to form a joint above the horizontal strip.

Referring more particularly to Figure 9, a modified form of joint installer is illustrated for installing a joint strip somewhat similar to that indicated in Figure 1. According to this machine 65 an inverted T-shaped blade 64 is provided which forms the longitudinal alining blade for the doubled and folded joint strip material 65. This blade 64 is trailed through the concrete mass 22 with its horizontal flange lowermost and submerged to a desired depth and with its vertical flange extending upwardly from the horizontal flange. The forward ends of the horizontal flange terminate short of the vertical flange and are curved upwardly to form runners or skids 66. The vertical flange extends forwardly beyond the skids 66 and constitutes a cutting blade 67 for grooving the concrete.

To the blade 67 are affixed the arms or brackets 68 which are assembled to the movable carriage and secured upon the carriage by supports which engage through the vertical slots 69 admitting of the vertical adjustment of the device from the carriage. The roll of joint material is indicated at 70 and is carried upon a shaft 71.

mounted in the bracket arms 68. The joint material 70 is brought down from the roll and beneath the deforming member 72 which is disposed at the mouth of the longitudinal shield 73. The joint material is shaped by the member 72 and the shield 73 about the alining blade 64, and the strip 65 in the doubled condition is left in the concrete while the blade 64 and shield 73 move forward longitudinally, thus depositing the strip 65 in the concrete. The bent portion or bight of the strip 65 is disposed uppermost or toward the surface, thereby producing a joint such as shown in Figure 10.

The outside shield 73 seats on the base or flange of the longitudinal blade 64 so that the joint material 65 will be free from any vertical pressure which might be produced because of finishing operations or other implements that might bear down on the shield 73.

Such pressure might cause a binding of the strip 65 and prevent its free movement over the blade 64 and under the shield 73. In dotted lines the shield 73 is shown as swung out of position or out of contact with the remaining parts of the apparatus. To effect this an arm 74 is provided being secured to the shield 73 as indicated at 75 and being pivoted at its other end upon the shaft 71. The shield 73 is swung out of operative position in order to facilitate inspection and cleaning of the apparatus. A float member 76 operates over the plastic material. This float member has a raised portion 77 so that excess concrete material may be retained longitudinally over the joint installing apparatus, because some surplus material is required at this point longitudinally along the joint line, as, after the apparatus has passed through the concrete and the strip 65 is left in position, there will be required a certain amount of concrete or plastic material to fill the space previously occupied by the members 64 and 73; it being understood that the final finishing operation over the surface of the concrete and over the strip 65 will be performed after the members 64 and 73 have been moved forward.

Figure 10 shows the inverted channel strip 65 in position showing the small crack at the top of the concrete. The slabs will crack and may be held together by dowel rods as previously explained.

Referring more particularly to Figure 11 another modification of the machine is shown involving a longitudinal joint blade 78 consisting of an upright U-shaped member having outwardly extending flanges 79 on its upper free edges. These flanges 79 are upon the intermediate portion of the joint blade 78 only. Such flanges begin at a point behind the front plow end 80 of the joint blade and they terminate short of the rear end of the blade 78. These flanges 79 form convenient supports for a bracket 81 having slotted side legs 82 through which extends the vertically adjustable shaft 83 of a rotary disc 84. The shaft 83 is carried in a fork 85 supported adjustably on the lower end of the screw shaft 86 threaded through the bracket 81 and rotatable by means of the hand wheel 87 to adjust the disc 84 vertically through the trough of the U-shaped blade 78. The disc constitutes the shaping member for the joint strip 88 which is fed from the roll of joint material carried upon the shaft 89 fitted in the arms or brackets 90.

The standard 91 to which the arms 90 are affixed and which carries the blade 78 is supported

from the transverse frame of the carriage 92. The standard 91 is pivotally or otherwise secured to a cross head 93 capable of vertical adjustment on the guides 94 carried by the frame 92. This cross head is engaged by an adjusting screw 95 which is threaded through a support 96 which may be affixed to the guides 94 or to some other fixed part of the frame. By manipulation of the hand wheel 97 the longitudinal blade 78 may be moved up and down to and from the plastic concrete. As before stated the blade 78 has a plow-shaped forward end 80 which opens up the concrete as the machine is moved forward. The rear portions of the flanges 79 are secured to the workmen's platforms 98 which may extend the full length of the carriage and are supported for vertical adjustment from the carriage by means of adjusting screws 99 secured to the platforms and extending through threaded brackets 100 upon the carriage frame. Lateral adjusting screws 101 are shown as engaged through the metallic straps 102 and abutting against the side edges of the platform 98. These straps 102 are slotted, as indicated at 103 to receive the adjusting nuts and bolts 104 engaged with the platforms.

By loosening the nuts and manipulating the adjusting screws 101, the platforms 98 may be shifted toward or from the blade 78. Thereafter the nuts 104 are tightened. The straps 102 are connected with the rear portions of the flanges 79 as indicated at 105.

In operating the device, the carriage 92 is moved longitudinally over the roadway, and the joint strip 88 is unreeled from the roll and passed under the disc 84. The disc is moved downwardly to the proper depth so that the joint strip 88 will be folded into a U-shaped member within the forming trough or blade 78. Being of flexible material, the strip 88, when it leaves the disc 84 will be irregular as to its upper edges. In other words it will be wavy. Where a perfectly alined joint is required it will be desirable to insert the metal alining bars 106 within the folded strip whereby to temporarily support such flexible joint strip to longitudinal alinement. One or more additional sections 107 may be provided for the alining bar having coupling means 108 between the sections. These coupling parts 108 will interlock with adjacent ends of companion bar sections. These bars are left in position until the concrete has taken its initial set; or they may be left in position until after the concrete has hardened; whereupon such bars may then be lifted vertically out of position within the folded strip 88.

Such alining bars therefore may be used over and over again. The transverse surfacer 109, which may be attached to the machine or operated manually over the surface of the plastic concrete and over the top surface of the joint strip 88, completes the finishing operation.

In Figure 12 is shown a sectional view of a modified joint strip 110, which is automatically deformed progressively as it passes through the longitudinal deforming and depositing blade. The flanges 111 serve as anchors to support the deformed strip in the plastic concrete. Sealing material 112 is poured into the open joint to provide a seal.

Referring more particularly to Figure 13, 113 represents a portion of the movable carriage which is supported on the side forms and moves longitudinally over the roadway. Carried on a frame 113 are depending slotted brackets 114 for slidably receiving parts of a head 115 which is 75

vertically adjustable by means of the adjusting screw 116. Pivotal or otherwise secured to the head, as indicated at 117, are two longitudinal members 118 which are spaced apart approximately one-half inch, such members being secured together at their forward ends by the head 115.

The bottom faces of these members 118 are of a desired width, say six inches each and have a flat surface which contacts with the top surface of the concrete. The members 118 are formed in the shape of runners at the forward end, as indicated at 119, in order to facilitate the movement of the members through the plastic material. The rear portions of the members 118 are reduced in width as indicated at 120, so that the rear end portions of these longitudinal members will converge into a narrow gauge-like structure which will occupy less space laterally over the surface of the roadway, thereby facilitating the finishing of the concrete closer to the zone of the installed joint. At the rear the runners 118 are connected together by a yoke 121.

Workmen's platforms are shown at 122 extending outwardly and spaced from the runners 118. On these workmen's platforms are mounted supports 123 for supporting the rear end of the joint installing apparatus. The bearings are slotted as indicated at 124 and vertically adjustable in the slots are bearing blocks 125 for receiving the shaft 126. The blocks 125 are adjustable through adjusting screws 127.

The shaft 126 supports the rear portion of the runners 118 so that through the adjusting screws 127 at the rear and the adjusting screw 116 at the front, the runners 118 will be vertically adjustable throughout the entire length thereof. The adjustment is independent at both front and rear parts of the device. Lateral adjustment is also provided by the collars 128 provided with set screws 129 for securing same to the shaft 126 outside of the supports 123. The longitudinal members or runners 108 are provided with up-standing arms 130 and 131 carrying shafts 132 and 133. One or both of these shafts may be mounted for vertical movement as for instance by being mounted in the bearing blocks 134 vertically adjustable in slots 135 in the arms 131, the adjustment being accomplished by means of adjusting screws 136. On these shafts 132 and 133 are rollers 137 and 138 which shafts and rollers are rotated by means of the sprockets 139 and 140 and the connecting chain 141. With one of the shafts is associated a drive sprocket 142 coupled to a chain 143 which extends to a suitable power plant on the carriage. A belt 144 extends over the rollers 137 and 138 and cleaving implements 145 are carried by said belt.

These cleaving implements extend down between the runners 118 and move through the plastic concrete within the space defined between the vertical inner flanges 146 of such runners 118. The runners are also preferably provided with vertical outer flanges to form a channel shaped reinforced runner, although this particular construction is not necessary. While the machine will move in the direction of the arrow A, the chain 141 and the cleaving implements 145 will be driven in the direction of the arrow B. It will be understood that a sprocket chain may be used in lieu of the belt 144. The cleaving implements may be of any desired shape, preferably having outer rounded end portions, in order to facilitate movement through the concrete in the same direction in which the machine

is moving. It will be understood that this cleaving implement may be driven faster than the carriage or machine in order that they may progress through the plastic concrete relatively to the movement of the machine, and in fact 5 may be moved through the concrete even though the carriage is stopped. Such cleaving implements will open up the concrete in preparation for the installing of the joint material. The joint material is carried in a roll 147 on the shaft 126 10 rearwardly of the cleaving implements 145.

The joint strip is unreeled from the roll 147 and moved down under the disc 148, being automatically folded when forced down between the spaced blades or runners 118 and being depressed 15 into the plastic concrete by the disc 148 which extends between the runners or blades 118. Any of the previously illustrated and described implements for installing the joint material may be substituted if desired. The disc may be carried 20 by a wire or other yoke 148 pivotally mounted in the supports 123 or upon other suitable fixed part. It may be desired to reinforce temporarily the folded joint strip 147 in order to hold the joint strip to alignment while the finishing of the concrete is performed over the top of the strip. Consequently alignment plates or bars 150 may be inserted within the folded joint strip 147 whereby to temporarily hold the strip in an expanded position and to true alignment permitting 30 the finishing of the concrete over the strip either by hand method or by mechanical method as indicated by the implement 151. It may also be desirable to install joint strips 152, which may consist of premolded material intended to remain 35 in place or such strips 152 may consist of a metal member which may be removed in order to form a groove. The metal member may correspond to the members 37 and 31a of Figure 7.

After the metal member is removed the groove 40 may be filled with a sealing material. When a premolded strip is employed or a removable metal strip used, the folded joint strip 147 may or may not be installed.

Referring to Figure 14, this figure corresponds 45 to Figure 28 of the parent application aforesaid. In accordance with this form of the invention a float 153 is shown having slots through which one or more discs 154 project downwardly into the concrete for cutting a groove in the concrete, 50 said float being adjustable vertically by means of adjusting screws 155. A pair of discs 156 is mounted in a hinged arm 157 to move in the groove or slot 158 formed by the discs 154. The arm is shown to be hinged at 159 upon an appropriate part of the carriage or machine frame 160. The joint strip is indicated at 161, the same being inserted in the groove 158 back of the float 153 and in advance of the discs 156, the discs acting to force the joint strip 161 down 60 into the groove whereby to properly install the same.

Figure 1—A represents a combination traffic line and joint, in which 22 represents the plastic concrete and 21a designates premolded ribbon, 65 which may consist of asphalt or any suitable material, having a color other than that of the surface of the roadway whereby to produce a distinct and contrasting traffic line.

This traffic line material would be desirable in 70 the width of approximately four inches and is embedded in the plastic concrete progressively as the installing implements move over the roadway and simultaneously the joint strip 59a is installed, it being understood that the implement 75

for installing this material may consist of the blade as shown in Figure 8, wherein it appears that this blade 52, 61 which is T-shaped installs the flat strip 21 and the joint strip 59. It will be noted that in Figure 1—A the position of the strips 59a and 21a is reversed with respect to Figure 8; namely the strip 21a is placed in the top surface of the road to form a traffic line instead of embedding it under the surface of the road 10 as illustrated in Figure 8.

It will be understood that this material 59a and 21a is installed by a T-shaped tubular member having the cross section as indicated at 52a and 61a in Figure 1—B.

Figure 13—A shows the cutter projecting down through the slot and into the plastic concrete. In this figure 22 represents the plastic material, 146a represents the spaced guides, which are supported and moved over the plastic concrete by a 20 suitable movable carriage. The guides may rest on the plastic concrete, if desired, or may be elevated slightly above the plastic concrete. A plurality of cleaving implements 145b, as illustrated in Figure 13, are moved longitudinally between 25 the guide members.

The implements have blade portions 145b, which move in the plastic concrete to form a cleavage. This cleavage may afterwards be filled with suitable joint material as before described.

In Figure 13—B are shown spaced blades having no inside vertical flanges. In this figure also appear cutting implements 145b which reciprocate back and forth while supported on the guides. The guide members, it will be understood, are supported on the carriage, and the cutters are reciprocated back and forth on the guide members with the cutting implement projecting down into the plastic concrete to cleave the material. It will be understood that a series of discs 30 145c may be also used as cleaving implements. These discs will move back and forth while supported on the guide members. The lower portion of the discs would project into the plastic concrete to cleave the material and the discs are reciprocated back and forth on the guide members while the carriage is being progressively moved forward over the plastic concrete with the guide members in contact with the plastic concrete or as stated before elevated slightly above 45 the surface of the material.

It is to be understood that the machine may move back and forth several times over the roadway to cleave the concrete for a distance of fifty to one hundred feet, and, on the last forward pass, the joint may be installed.

The various implements may be used independently of one another as may be desired.

It is obvious that various changes and modifications may be made in the details of construction 60 and design of the above specifically described embodiment of this invention without departing from the spirit thereof, such changes and modifications being restricted only by the scope of the following claims.

65 What is claimed is:—

1. A joint installing device comprising a trough-shaped longitudinal member for movement longitudinally in the plastic concrete, a longitudinal blade supported within the first named member, the longitudinal blade adapted to receive over the top thereof a joint strip, and means for folding the strip over the blade.

2. A joint installing device comprising a longitudinal guide member, a blade in said guide member adapted to receive a ribbon joint strip

over the upper portion thereof, and means co-operating with the blade for folding the joint strip downwardly upon opposite sides of said blade.

3. A joint installing device comprising a trough-shaped guide, a flat blade lying through said guide and having its forward upper edge inclined, a joint strip received over the upper inclined edge of the blade, and forming members straddling the blade at its inclined portion for folding the joint strip downwardly over the sides of the blade.

4. A joint installing apparatus, consisting of a wheeled carriage operating on side forms and spanning a road under construction, a trough-shaped longitudinal member to be moved longitudinally in the plastic concrete, a longitudinal blade supported within the first named member, means for movement of the joint strip over the top of the blade, and means for folding the strip over the blade and moving the member and the blade longitudinally of the roadway to deposit the folded strip rearwardly of the member and the blade.

5. An improved joint for plastic material, said plastic material having a groove in the upper portion only thereof, a flat strip of joint material embedded substantially horizontally in the plastic material immediately below said groove and spaced above the base of the plastic material, 30 said strip being wider than the groove and having plastic material lying in contact with the strip continuously below the same and above the strip at opposite sides of the groove, and sealing means placed in the groove above the strip.

6. An improved joint for plastic structures, said plastic structure having a groove in the upper surface portion of the structure, the base of the groove being spaced above the base of the plastic structure, comprising a thin flat ribbon 40 strip of waterproof material placed with its flat side dimension substantially in the horizontal and submerged within the plastic structure immediately below the groove, said strip being wider than the groove and having its side portions directed upwardly the plastic material of the structure lying above and below said side portions and in contact therewith and sealing material in the grooves above said joint strip.

7. A joint installing apparatus comprising a longitudinal trough-shaped member adapted to be moved in the plastic material, a longitudinal blade adjustably supported within said member, and means for holding joint material for movement under the blade to be deformed by the blade and deposited in the plastic concrete rearwardly of the blade and said member.

8. A joint installing apparatus, comprising a wheeled carriage operating on side forms and spanning a road under construction, a longitudinal trough-shaped member to be moved in the plastic material, a longitudinal blade adjustably supported within the member, and joint material mounted on the apparatus for movement under the blade to be deformed by the blade and deposited in the plastic concrete rearwardly of the blade and said member.

9. A joint installing apparatus, comprising a longitudinal trough-shaped member to be moved in plastic concrete, a longitudinal blade supported within the member, means mounted on the member for vertical adjustment of the blade, and means for movement of the member and the blade through the plastic concrete to produce a joint rearwardly of the blade.

10. A joint producing apparatus, comprising a wheeled carriage operating on side forms and spanning a road under construction, a longitudinal trough-shaped member supported on the carriage, means for vertical adjustment of the member on the carriage, a supply of joint material supported by the member to be moved longitudinally through the member, a longitudinal blade supported on the member, and means for movement of the blade into the member to deform a joint strip to be passed through the member to be installed in plastic concrete rearwardly of the member.
11. The method of installing joints in plastic concrete, consisting of moving a trough-shaped member longitudinally through the plastic material, simultaneously moving a strip of joint material through the member and deforming the strip by means of a second member inserted within the first-named member, finishing the plastic material over the second-named member, and moving both members longitudinally of the roadway to deposit the joint strip rearwardly of both members.
12. The method of producing joints in a concrete road, consisting of the movement of a longitudinal trough-shaped member through the plastic concrete, a second longitudinal member associated with the first-named member, a supply of joint strip to be moved longitudinally through the first-named member and to be deformed by the second-named member and to be installed in the plastic concrete rearwardly of the first-named member, moving the second-named member longitudinally through the deformed joint strip, and means associated with the second-named member to finish the plastic material longitudinally over the joint strip.
13. The method of installing joints in a concrete roadway under construction, consisting of the movement of a wheeled carriage longitudinally of the roadway, simultaneously moving a tubular blade through the plastic material, moving a joint strip longitudinally through the blade and deforming the strip by a second longitudinal blade mounted within the first-named blade, depositing the deformed strip in the plastic concrete under the second blade, and moving the second blade longitudinally from the deformed strip.
14. A joint producing apparatus comprising a substantially U-shaped guide member, means for holding a strip of joint material at the forward portion of the guide member, a blade in the guide member for deflecting the joint strip downwardly into the trough-shaped member and for forming the joint strip into substantially U-shape, said blade extending rearwardly of the U-shaped guide member.
15. The method of producing joints in a concrete surfacing structure, consisting of the movement of ribbon joint material through a longitudinal blade, said ribbon being submerged flatways in the plastic material, means for producing a cleavage in the plastic material over the ribbon, and means for moving the apparatus through the plastic material to deposit the ribbon rearwardly of the blade.
16. The method of producing a longitudinal joint in a concrete roadway under construction, consisting of submerging a flat ribbon longitudinally of the roadway at a point below the surface, cleaving the plastic material between the surface of the road and the ribbon to produce a groove above the ribbon and introducing joint material therein to seal the groove.
17. An apparatus for installing joints in concrete roadways under construction comprising a cleaving implement for movement through the concrete, and intersecting tubes following the cleaving means in the concrete for depositing joint strips angularly to one another.
18. An apparatus for installing joints in concrete structures comprising a blade adapted to receive joint material thereover, and an inverted U-shaped member extending over said blade for doubling the joint strip over the blade.
19. An apparatus for forming joints in concrete surfacing material comprising a longitudinally moving blade for receiving joint strip thereover, an inverted trough-shaped shield member extending over said blade and in spaced relation therefrom to receive the joint strip therewithin, and a joint strip deforming means at the forward portion of said shield member.
20. An apparatus for the installing of joints in concrete roads comprising an inverted T-shaped blade submerged in the concrete and movable longitudinally therethrough, an inverted trough-shaped shield resting upon the flanges of the blade and adapted to receive therewithin joint strip material to be folded over the blade, means for supporting joint strip material, and joint stripping deforming means carried at the forward portion of said shield member, and means for supporting the shield member for movement toward and from said blade.
21. The herein described method for forming joints in plastic constructions, which consists in moving a blade longitudinally through plastic construction, folding a joint strip with its central portion upon said blade and with its side portions downwardly upon opposite sides of the blade, and moving the blade longitudinally to deposit the joint strip in the concrete.
22. An apparatus for installing joints in concrete roadways comprising a substantially trough-shaped guide, means for folding joint strip into said guide with its free edges uppermost, and means for straightening and alining the free edges of the joint material.
23. An apparatus for installing joints in concrete roadways comprising a substantially U-shaped member, a carriage carrying said member for movement through the concrete, means for supplying to said member a foldable strip of joint material, and an adjustable disc extending into said member for folding the joint strip material therein.
24. An apparatus for installing joints in concrete roadways comprising a trough-shaped guide member, a plow at the forward portion of the member, a carriage for adjustably supporting the plow and member for movement through the concrete, means for supporting a roll of foldable joint material above the forward portion of said member, a vertically adjustable disc extending into said member for folding the joint strip therein, and a laterally adjustable workman's platform on the carriage at the side of said member.
25. A joint installing apparatus, consisting of spaced longitudinal members to be moved longitudinally over plastic concrete, a plurality of joint cleaving members mounted for movement through the plastic concrete with a space provided between the members to produce a longitudinal cleavage in the material, and means following for the installation of joint material within the cleavage.
26. A joint installing apparatus comprising

longitudinally extending spaced runners, a carriage to which said runners are adjustably connected, cleaving implements moving forwardly in the direction of movement of the carriage through the space between said runners and down into the plastic concrete, means for supporting and moving said cleaving implements, joint material supported back of the cleaving implements in position to enter the cleavage between the runners, and means for forcing the joint strip into the concrete and doubling same.

27. A joint installing apparatus comprising a pair of spaced apart longitudinally extending runners for movement upon the surface of plastic concrete, a carriage, means for adjustably supporting the runners from the carriage, a movable endless belt supported above said runners, cleaving fingers having curved end portions mounted

on said belt and positioned to move through the concrete between said runners, and means at the rear of said belt for installing joint material in the cleavage made between said runners.

28. An apparatus of the kind described comprising a float movable over plastic concrete, a cutting tool carried by said float and movable in the plastic concrete for forming a groove to receive joint material to be inserted behind the float, and means following the float for installing the joint material.

29. In joint installing apparatus, a slotted float movable over plastic concrete, a plurality of aligned cutting discs carried by the float and extending through the slots therein, and pivotally supported joint installing means coupled to follow said float.

JOHN N. HELTZEL.
